UNITED STATES PATENT OFFICE.

JAMES M. BLAISDELL, OF WINTHROP, MASSACHUSETTS.

DEVICE FOR FEEDING FIBER TO FIBER-TREATING MACHINES.

SPECIFICATION forming part of Letters Patent No. 576,298, dated February 2, 1897.

Application filed May 18, 1896. Serial No. 591,996. (No model.)

To all whom it may concern:

Be it known that I, JAMES M. BLAISDELL, of Winthrop, county of Suffolk, and State of Massachusetts, have invented an Improvement in Devices for Feeding Fiber to Fiber-Treating Machines, of which the following description, in connection with the accompanying drawings, is a specification, like letters on the drawings representing like parts.

- 10 The present invention relates to a machine for feeding a fibrous substance, such as card and picker waste, to a machine for treating the same, such, for example, as a cleaner, or spinner's waste to a thread-extractor, the nature of the material to be fed being such that it cannot be fed by gravity, but has to be positively acted upon, it having been usually the custom to feed by hand, thus requiring an attendant for each machine.
- 20 The present invention relates to a machine operating on substantially the same principle as that shown and described in Letters Patent No. 545,189, granted to me on the 27th day of August, 1895, in which the feeding is accomplished by the operation of feeding devices which act upon the material to force the same through an opening into the machine which is to be fed, in combination with devices for bringing the material into a position to be operated upon by said feeding devices, it being necessary to provide means for supplying the said feeding device with the material in bulk.
- 30 The present invention relates to an improved machine for this purpose; and it consists mainly in novel devices for properly supplying the material to the feeding devices, which may be and are shown as reciprocating plungers, substantially as in my prior patent above referred to, operating to positively feed the material thus supplied through an opening to the machine in which the material is to be treated.

The machine embodying the present invention consists mainly in the combination, with the feeding devices proper, (in this instance the reciprocating plungers,) of a feed-hopper containing an agitating or stirring device adapted to be kept in motion by a suitable connecting mechanism with the source of power that operates the plungers, the said stirring device being so arranged that it tends

to force material placed in the hopper toward the feed-opening, where said material is operated upon by the plungers and forced into and through the feed-opening of the treating-machine.

The invention further consists in novel means for supporting the machine, whereby it is easily removed from its feeding position with relation to the treating-machine which is being fed, in order that the cover of said treating-machine may be rendered accessible, as is necessary from time to time during the operation thereof.

Figure 1 is an elevation of the machine embodying the invention; Fig. 2, a similar elevation taken on a plane at a right angle to that of Fig. 1; Fig. 3, a sectional elevation of the machine, showing the stirring device contained in the hopper; and Fig. 4, a longitudinal section on a plane near the top of the hopper, showing the main portion of the operating mechanism in plan.

The feeding devices proper are herein shown as reciprocating plungers a , which are adapted to alternately move into and out of an opening b^2 at the bottom of the hopper b , said opening being over an opening A^2 in the casting of the treating-machine A , which is to be supplied with material, and may be operated in any suitable way. As herein shown, the said plungers are each provided with a slotted cross-head a^3 , having a slide-pin a^3 cooperating with oppositely-extending cranks a^4 on a shaft a^5 , driven in any suitable way, so that the rotation of said shaft produces an opposite reciprocation of said plungers a .

In order to properly supply the material to the opening b^2 , where it will be operated upon by the said feeding devices or plungers a , the hopper b is provided for the material to be fed, and the said material within the hopper is acted upon by a stirring device consisting of a number of blades b^3 , carried by a rotating frame b^4 , mounted on a vertical spindle b^5 near the center of the hopper, so that the said blades extend outward toward the periphery thereof and tend to carry the material in the hopper around the same, the said blades being preferably, as shown in Fig. 4, rearwardly inclined to the direction of rotation, whereby they tend to force the material outward toward the periphery of the hopper,

so that in the travel thereof it is brought directly over the opening b^2 , through which it is thrust by the plungers a . In order to increase this tendency, the frame b^4 , which carries the blade, is surmounted by a deflector b^6 , preferably in the form of a cone, by which the material contained in the hopper is deflected toward the sides of the hopper, where it is operated upon by the stirring-blades b^8 , as above described.

Below the conical deflector there is preferably arranged a stationary conical or slanting surface b^7 , the blades being bent downward, as shown in Fig. 3, so as to travel close to the said surface, the object being to crowd the material downward and outward as the stirring device rotates.

The opening b^2 , through which the feeding devices proper, namely, the plungers a , reciprocate, is arranged, as shown, close to the periphery of the hopper b , the walls of the said hopper being flared or spread somewhat at that point, as shown in Fig. 4, so as to afford a space between the ends of the blades b^8 and the walls of the hopper over the said opening in order that the plungers may operate without interfering with the rotation of the stirring device. During the operation of the machine, therefore, the plungers alternately reciprocate, while the stirring device rotates, tending to force the material toward the sides of the hopper and carry it around the same, so that when it reaches the opening b^2 it is forced into the space b^{20} between the wall of the hopper and the ends of the stirring-blades and under the plungers and forced thereby downward through the opening.

The walls of the hopper, as shown, are bent inward at the sides of the opening b^2 , thus forming a recess or space b^{21} for the feeding devices, and, as indicated in Figs. 3 and 4, the inwardly-extending portion of the wall at the side toward which the stirrers travel in the rotation of the stirring device is cut away at substantially the level of the bottom of the feeding devices or plungers when at their maximum height, so that the material in the hopper is pushed along to a position directly over the opening. The inwardly-extending wall on the opposite side of the space b^{21} , however, is preferably unbroken, extending, as indicated at b^{22} , Fig. 4, to the bottom of the hopper, thus forming an abutment for the material carried around by the stirring device, whereby it is checked after reaching a position over the opening b^2 .

As a further check to the material when it has been carried to feeding position a hook or projection b^{23} is preferably provided extending inward beyond the inwardly-extending portion b^{22} of the wall of the hopper, somewhat above the opening, the said hook, as shown, standing over the stirring-blades, so that it tends to stop a portion of the material which would otherwise be carried by. The said hook, however, is not large enough to prevent any superfluous material from being

carried onward by the stirrers to be operated upon when it is again brought to a position over the opening. The said stirring device may be constructed and arranged in any suitable way and driven by any convenient operating mechanism, and, as herein shown, the cone b^6 is secured to a vertical hub b^8 , forming part of the frame b^4 , which consists, as indicated in dotted lines, Fig. 4, of a number of arms extending outward from said hub and connected at or near their outer ends with a gear b^9 , adapted to be driven by a worm c , as will be hereinafter described.

The blades b^8 extend through slots b^{12} in the wall of the cone b^6 and are fastened at their inner ends to a collar b^{13} , secured, as by a set-screw b^{14} , upon the hub b^8 , so that the frame b^4 , the cone b^6 , and the said blades b^8 all travel simultaneously by the operation of the worm c .

The stationary surface b^7 consists of a piece of sheet metal having a central opening through which extends the hub b^8 , the said piece b^7 being in the shape of a truncated cone having the edges of its base secured to the bottom of the hopper, which preferably consists, as shown, of a disk or plate B , provided with a flange B^2 , upon which rests the edge of the piece b^7 , which may be soldered or otherwise secured thereto, said disk or plate also having a flange B^3 , within which is contained the wall of the hopper b . The said disk B also serves as the main base or support for the remaining parts of the machine.

The power may be applied and transmitted to the various working parts of the apparatus in any suitable way, and, as herein shown, the shaft a^5 , which, as has been described above, is connected through the cranks a^4 and slotted cross-heads a^2 to the plungers a^7 , is driven by a gear a^6 , meshing with a gear a^7 upon a counter-shaft a^8 , provided with a pulley a^9 , adapted to be driven by a belt.

The shaft a^5 and counter-shaft a^8 are supported upon an extension B^4 from the base-plate B , brackets B^5 being provided for this purpose, which are secured on the said extension. The bearings for the shaft a^5 are formed, as shown, at the tops of the brackets B^5 , the upper members of said bearings being preferably formed in supplemental brackets B^6 , bolted or otherwise secured to the top of the bracket B^5 , said supplemental brackets extending upward above the gear a^6 and affording a support for a guide a^{20} , consisting of a plate or bar extending across from one bracket to another and provided with openings a^{21} , through which extend rods a^{22} , connected to the cross-heads a^2 . A similar guide is provided extending across the lower portion of the brackets B^5 , and each cross-head a^2 is provided with a similar rod extending downward therefrom to the said lower guide, as clearly shown in Fig. 2, so that the said cross-heads are properly supported in their reciprocating movement.

The counter-shaft a^8 is supported in a bearing B^{50} at the lower portion of the bracket B^5 .

In order to drive the worm c , which meshes with the gear b^9 to rotate the frame which carries the stirring device, the said worm is mounted on a shaft c^2 , extending through an opening c^3 in the wall of the hopper and having a bearing c^4 at one end within the hopper and a bearing c^5 at the opposite end mounted on a portion of the bracket B^5 or extension thereof, and a gear c^6 is secured to the end of the said shaft c^2 , meshing with an intermediate gear c^7 on a short shaft c^8 in a bearing c^9 , having also a member c^{10} of a so-called "skew-gear" meshing with the other member c^{12} upon the end of the shaft a^5 , as best shown in Fig. 2.

The shaft c^2 , as shown in Fig. 3, passes below the edge of the rotating frame b^4 and also under the surface b^7 , the bearing c^4 , the shaft c^2 , and the worm c being thereby covered and protected from the material within the hopper, so that they will operate freely without becoming clogged or fouled.

To provide for the removal of the device from the top of the machine to which it is applied in order that the cover thereof may be lifted when necessary, the base portion B is provided with downwardly-extending ears or lugs B^7 , provided with openings, through which extend supporting-rods d , supported by brackets d^2 , adapted to be secured to the machine which is being fed, so that the feeding device is capable of being slid along said rods away from the top of the machine to which the device is applied, and when thus removed from the machine is supported upon the said bracket. To facilitate this operation, the handle e is provided and attached to a rock-shaft e^2 , supported in lugs e^3 , secured to the outside of the base-plate B , the said rock-shaft having a pawl e^4 , connected therewith at each end, adapted to coöperate with a notch d^3 in each of the rods d , so that when the device is in operative position said pawls will engage with the said notches and prevent the accidental removal thereof, while if it is desired to remove the machine the handle e may be first lifted to disengaging position and the machine then pulled along the guide-rods d by means of said handle until it is supported by the brackets d^2 and the hopper portion removed from the cover of the machine to which it is applied.

It is not intended to limit the invention to the specific construction and arrangement herein shown and described, since obvious modifications may be made without departing from the invention; nor is it intended to limit the invention to the combination of the stirrers or means for presenting the material to the feeding device proper with any special form of such feeding device, since the operation of that portion of the apparatus is not dependent upon the specific construction and arrangement of said feeding device, it being obvious that the material might be equally

well presented to a feeding device of any suitable construction.

I claim—

1. The combination with the feed-hopper 70 having an opening through the bottom near the periphery thereof, of a stirring device comprising a rotating carrier within said hopper having wings or blades adapted to carry material therein from the middle toward the periphery thereof, and a feeding device for positively feeding said material into said opening, substantially as described.

2. The combination with the feed-hopper, 80 of oppositely-reciprocating plungers movable longitudinally through an opening at or near the periphery of said hopper, a stirring device consisting of a rotating carrier within said hopper, and a series of transverse blades extending from said carrier toward the periphery of the hopper, substantially as described.

3. The combination with a feed-hopper adapted to contain fibrous material and provided with a feed-opening through the bottom 90 and near the periphery thereof; of a stirring device comprising a rotating carrier having a series of blades or wings along the periphery thereof and extending therefrom substantially to the periphery of the hopper, a centrally-located deflecting-surface adapted to deflect the contents of the hopper toward said wings or blades, and a feeding device for positively feeding said contents into the feed-opening, substantially as described.

4. The combination with a substantially cylindrical feed-hopper having a portion of its wall extended beyond the periphery of a true cylinder, of a stirring device comprising a rotatable carrier having wings or blades extending radially from the center of said hopper to the periphery of the main portion thereof, a spindle coaxial with said hopper upon which said stirring device is mounted, and a feed-opening from the hopper adjacent to said extended portion of the wall thereof, substantially as described.

5. The combination with the hopper provided with a feed-opening near the periphery thereof, of a floor or surface for said hopper 115 sloping upward from the periphery toward the center thereof, a stirring device comprising the rotating carrier having a conical deflecting-surface rising above said sloping floor, a series of wings or blades extending outward 120 from said conical deflector toward the periphery of the hopper, said blades being bent or inclined to the rear with relation to the direction of rotation of said carrier, and a feeding device for positively feeding material into the 125 said feed-opening, substantially as described.

6. The combination with a hopper, of a feed-opening therein, a reciprocating plunger or plungers movable into and out of said opening, a stirring device consisting of a series of 130 blades or wings adapted to carry the material within said hopper toward said feed-opening,

a rotating carrier for said blades within said hopper and connecting mechanism whereby said plungers are reciprocated, and said carrier rotated, substantially as described.

- 5 7. The combination with the feeding-machine comprising a hopper having a feed-opening near the periphery thereof, stirring devices adapted to carry material in the said hopper from the center to the periphery thereof, feeding devices proper, and operating mechanism therefor, substantially as described, of a supporting - bracket therefor adapted to be secured to the machine to which fiber is to be fed, the said feeding device being movable along said bracket to and from its operative position, substantially as described.
- 10 15 8. The combination with a hopper, of a feed-

opening therein, a reciprocating plunger or plungers movable into and out of said opening, a stirring device consisting of a series of blades or wings adapted to carry the material within said hopper toward said feed-opening, a rotating carrier for said blades, an inwardly-projecting portion of the wall of the hopper beyond the feed-opening in the direction of rotation of said stirring device, and a hook or projection projecting inward over said blades, substantially as described.

In testimony whereof I have signed my name to this specification in the presence of two subscribing witnesses.

JAMES M. BLAISDELL.
